CLAIM

We claim the ornamental design for an iron golf club head, as shown and described.

DESCRIPTION

FIG. 1 is a top, rear perspective view of an iron golf club head of the present design;

FIG. 2 is a bottom, rear perspective view of the iron golf club head of FIG. 1; and,
